UNITED STATES PATENT OFFICE.

WALTER PIEL, OF NEW YORK, N. Y.

GASOLINE-SUPPLY SYSTEM FOR INTERNAL-COMBUSTION ENGINES.

Application filed November 19, 1919. Serial No. 339,238.

To all whom it may concern:

Be it known that I, WALTER PIEL, a citizen of the United States, and resident of New York city, in the county of New York and State of New York, have invented certain new and useful Improvements in Gasoline-Supply Systems for Internal-Combustion Engines, of which the following is a specification.

The invention relates to a liquid fuel feeding apparatus for internal combustion engines and is of the general type of such apparatus in which liquid fuel is elevated from a low supply tank to a position above the carburetor and in which the fuel thus elevated is periodically discharged from the elevated position so as to flow by gravity to the carburetor. It has been known heretofore to cause the liquid to be dumped into the elevated feed tank by reducing the pressure condition in this feed tank thus raising the liquid by suction and then to permit the liquid in the tank to actuate certain valvular mechanisms for controlling the discharge to the carburetor.

The primary object of this application is to provide a simple form of device of the class described featured by the fact that it can utilize the more or less wasted pressure factors in engine operation for the purpose of supplying the energy necessary to reduce the pressure in the feed tank.

The invention contemplates the utilization of the cooling system water, or the exhaust gases or the pressure force in the crank case to actuate an aspirating device arranged to exhaust the pressure in the feed chamber. It has been proposed heretofore to pass exhaust gases from the engine through the feed tank to effect this desired reduction in pressure, but such systems are obviously undesirable in that foreign substances are apt to be introduced into the fuel line.

In this disclosure it is proposed to pass this heretofore waste energy such as the exhaust gases through an aspirator with its suction vent open to the feed chamber and thus avoid any necessity of passing foreign bodies through the feed chamber. There is provided an effective, constant and positive tendency to exhaust the feed chamber and without the necessity of intentionally creating a source of power to effect the operation.

The invention therefore features economy in operation as well as initial construction and with these desideratum in view, the her-

metically sealing valve structures heretofore necessary have been practically eliminated as any small leakage in the device herein-after described will not have any material effect upon the successful operation of the device.

Another object of the invention is to provide a single commercially perfected type of device which, by the substitution of replaceable control nozzles, can be readily adapted to function with the different sources of pressures hereinbefore suggested.

Various other objects and advantages of the invention will be in part obvious from an inspection of the accompanying drawings and in part will be more fully set forth in the following particular description of one form of mechanism embodying my invention and the invention also consists in certain new and novel features of construction and combination of parts hereinafter set forth and claimed.

Referring to the accompanying drawings:

Figure 1 is a vertical sectional view taken on the line 1—1 of Figure 2 through a preferred embodiment of the invention;

Figure 2 is a plan view looking down upon the device shown in Figure 1; and

Figure 3 is a detailed sectional view showing a slightly modified form of aspirating device.

In the following description and in the claims, parts will be identified by specific names for convenience of expression but they are intended to be as generic in their application to similar parts as the art will permit.

In the accompanying drawings, there is shown an organization of parts which is somewhat conventional and include an upper or float chamber 10, hung from a flange 11 of a supporting top 12. From another flange 13 is hung a lower or feed chamber 14 enclosing the float chamber and provided with an air vent 14'. The float chamber is provided with a fuel inlet 15 extending through the top 12. The fuel inlet is connected to a suitable source of fuel supply positioned below the device illustrated as is usual in fuel feed systems of the character under discussion. Communication between the float chamber and the feed chamber is provided by means of a liquid discharge outlet port 16 positioned in the bottom of the float chamber. The bottom of the feed chamber is provided with an outlet 17 which

leads by means of a pipe connection 18 to the carbureter (not shown). The bottom of the feed chamber is also provided with a drain cock 20 leading from a depression 21 in the lower wall 22 of the feed chamber.

The top of the float chamber is provided centrally thereof with an air inlet 23, preferably closed by means of a screened cap 24 and designed to admit air into the float chamber when this chamber is discharging into the feed chamber. The port 16 is controlled by a downwardly opening valve 25 and the air inlet is likewise controlled by a needle valve 26. Both of said valves are mounted upon a connecting stem 27 and the parts are so arranged that both valves are simultaneously moved into either an opened or closed position depending upon the direction of movement of the stem. The float chamber is provided with a float 28 operatively connected, through a system of links 29 and levers 30 with a collar 31 on the rod 27 so that, when the float is at, or moving to or from, its lowermost position both of the valves are closed. The links are loosely connected to the levers so that the initial upward movement of the float will have no effect on the position of the closed valves but as the float approaches the upper limit of its movement, it will react through the levers and rod to simultaneously open both of the valves. In general it will be understood that the construction as thus far described resembles similar devices now known and that the invention primarily resides in the combination of aspirating devices of the type hereinafter described for actuating gravity feed tanks of the type hereinbefore described.

Referring particularly to the attachment shown at the top of the feed tank there is disclosed positioned on the top 12, or formed therewith, an aspirating device 32 which includes a straight bore 33 extending therethrough from end to end. The bore is constricted intermediate its ends to form a Venturi tube 34. The device is provided with a relatively small suction vent 35 opening from the tube 34 at or adjacent its point 36 of greatest constriction. This vent provides a constantly opened passageway to the upper portion of the float chamber. When the actuating pressure through the Venturi tube is a gaseous fluid, it is preferable that this vent be constantly opened, but under some conditions, as where the water of the cooling system is passed through this Venturi tube, it is suggested that it may be necessary to have some suitable check valve in the vent to prevent water from leaking into the float chamber.

The intake end of the Venturi tube is operatively connected to a suitable source of high pressure which source is indicated diagrammatically by the pipe connection

37. The discharge end of the Venturi tube may open to the outside air, if desired, or may lead to a muffler or to the return pipe of the water system, indicated diagrammatically by the pipe connection 38.

It is found that the operation of the device is improved by positioning one or more baffles beyond the point 36 of greatest constriction, which baffles apparently have the effect of breaking up the fluid pressure stream as it is passed through the Venturi tube. In Figure 1, one such baffle 39 is shown positioned in a coupling 40 arranged between the discharge end of the Venturi tube and the pipe connection 38. By this arrangement it is possible to readily connect the member; also to remove the baffle and in this way obtain access to the interior of the Venturi tube for the purpose of cleaning the same.

It has been found experimentally that the positioning of the vent 35 at the point of greatest constriction is an improvement over the positioning of the vent beyond this point and for this reason the invention contemplates the positioning of the vent either at the point of greatest constriction as shown in Figure 1 or in advance of this point as shown in Figure 3.

In order to adopt the device to operate with different pressures, the modified device shown in Figure 3 is suggested. In this modification the tube 32 may, or may not be constricted, as desired and as governed by other factors, but the effective constriction is provided by utilizing a replaceable nozzle 41 screwed into the intake end of the tube 32. Tubes with different size discharge nozzle ends 42 may be substituted for the nozzle illustrated. This form of replaceable venturi forming nozzle is of further advantage in that it permits the ready removal of parts which are most likely to become clogged.

In operation, it will be understood that the Venturi tube is constantly connected to some available source of pressure and that the fluid, gaseous in some cases, or as suggested, the liquid from the cooling system, is constantly forced through the Venturi tube. In passing therethrough it is broken up as is usual with injectors of this type and air is constantly withdrawn from the float chamber through the open vent 35.

Assuming that the float is in its lowermost position and that the air inlet and the discharge port are closed, the action of the aspirating device will reduce the air pressure condition in the float chamber, thus unbalancing pressures on the fuel and permitting the fuel to be elevated and discharged through the inlet 15 and into the float chamber. The rising liquid in the float chamber will act upon the float to raise the same and thus open the discharge port and air inlet.

Opening the valves permits the liquid to be discharged from the float chamber into the feed chamber as is well known in devices of this character. The movement of the float falling into its lowered position will restore the valves into their initially closed positions and the device is ready to have the operation repeated.

By means of a device of this character it is possible to utilize the waste energy available in internal combustion engine operation for the purpose of elevating the liquid fuel to the carburetor or to any other similar liquid receiving devices. Nothing more than ordinary care need be exercised with reference to the construction of the valves for even if some air should leak through the valve controlling the air inlet, it would merely mean a slight delay in the operation of the tank and any delay due to a slight leakage would be immaterial. Any available pressure, such as those suggested, acting through the Venturi tube would be ample to compensate for any such small leak. Again, should there be a slight leakage through the fuel controlling port it would not materially affect the operation of the device and would merely mean that there was a slight leakage into the feed chamber but this would in no way affect the economic actuation of the device.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. In a device of the class described, the combination of a float chamber, having an air inlet in the upper part thereof, and a fuel discharge port in the lower portion thereof, a float in said float chamber, a valvular construction including a pair of valves rigidly connected and controlled by said float for simultaneously closing both the air inlet and the fuel discharge port when the float is at or moving from a lowered position and for simultaneously opening both the air inlet and the fuel discharge port when the float approaches the upper limit of its movement, a feed chamber for receiving the discharge directly through said port and aspirating means carried above the float chamber continuously open to the upper portion of said float chamber and tending to reduce the pressure in said chamber, said aspirating means being continuously operated when fuel is being withdrawn from the feed chamber.
2. In a device of the class described, the combination of a float chamber, having an air inlet in the upper part thereof, and a fuel discharge port in the lower portion thereof, a float in said float chamber, a valvular construction controlled by said float for simultaneously closing both the air inlet and the fuel discharge port when the float is at or moving from a lowered position and for opening both the air inlet and the fuel discharge port when the float approaches the upper limit of its movement, a feed chamber for receiving the discharge from said port and an aspirating device provided with an intake end provided with means for connecting the same to some suitable source of fluid under pressure, said device also provided with a discharge end for discharging said fluid and with a vent intermediate the ends open to the float chamber for reducing the pressure in said float chamber and means within said aspirating device for breaking up the fluid as it is passed therethrough.
3. In a device of the class described, the combination of a float chamber, having an air inlet in the upper part thereof, and a fuel discharge port in the lower portion thereof, a float in said float chamber, a valvular construction controlled by said float for simultaneously closing both the air inlet and the fuel discharge port when the float is at or moving from a lowered position and for opening both the air inlet and the fuel discharge port when the float approaches the upper limit of its movement, a feed chamber for receiving the discharge from said port, aspirating means continuously open to the upper portion of said float chamber and tending to reduce the pressure in said chamber, said means including a conduit for passing a fluid under pressure therethrough without passing the fluid into the float chamber, said conduit having a Venturi constriction therein intermediate its ends and a baffle disposed beyond the Venturi constriction.
4. In a device of the class described, the combination of a fuel receiving receptacle, a top thereto bored therethrough to provide means for reducing the pressure condition in said receptacle thereby to elevate fuel into said receptacle, one part of the bore providing a Venturi tube having means at one end for connecting the same to a source of fluid under pressure and means at its opposite end for discharging said fluid exteriorly of the receptacle, and another part of said bore constituting a constantly open vent leading into the upper portion of the receptacle from a position in the tube in advance of the place of greatest constriction.
5. In a device of the class described, the combination of a fuel receiving receptacle, means for reducing the pressure condition in said receptacle thereby to elevate fuel

into said receptacle, said means including a Venturi tube having means at one end for connecting the same to a source of fluid under pressure and means at its opposite 5 end for discharging said fluid exteriorly of the receptacle, said tube provided with a constantly open vent leading into the upper portion of the receptacle, from a position in the tube in advance of the place of greatest constriction and said tube provided with a baffle disposed beyond said place of greatest constriction.

6. In a device of the class described, the combination of a fuel receiving receptacle 15 having a top, means for reducing the pressure condition in said receptacle thereby to elevate fuel into said receptacle integral with said top, said means including a Venturi tube having means at one end for connecting the same to a source of fluid under 20 pressure, means at its opposite end for discharging said fluid exteriorly of the receptacle, said tube provided with a vent leading into the upper portion of the re-

ceptacle, said receptacle provided with an 25 air vent distinct from said Venturi tube and replaceable means for varying the suction effect of the Venturi tube on the contents of the receptacle.

7. In a device of the class described, the 30 combination of a fuel receiving receptacle, a straight bore tube positioned above the receptacle and within the upwardly projected outlines thereof, a replaceable nozzle threaded into one end of said tube for controlling 35 fluid under pressure projected by the nozzle through said tube, said nozzle adapted to be connected to a source of fluid supply under pressure, said tube provided with a vent for placing the part of the tube adjacent the discharge end of said nozzle in fluid communication with the upper portion of the tank to reduce the air pressure therein.

Signed at New York city, in the county of New York and State of New York, this 45 5th day of November A. D. 1919.

WALTER PIEL.
